Attorney

UNITED STATES PATENT OFFICE.

JOHN WALDHEIM, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed July 3, 1922. Serial No. 572,396.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

The present invention relates to sound-deadening casings for typewriting machines; and more particularly to the type of casing into which the machine is inserted from the top; the casing having a cover which may be opened to permit of placement 10 and removal of the machine, and to permit of access to the machine for erasures and other purposes. Casings of the character mentioned have heretofore been made of sheet-metal or die-castings, lined with felt 15 or other sound-deadening material, cut into pieces of various shapes, and joined and held to the casing proper by various devices.

An object of the present invention is a casing having no sound-deadening wall-members other than the walls which form the frame of the casing; and in which, therefore, the number of parts and fittings may be reduced to a minimum.

In attaining this object of the invention, 30 the casing is constructed of beaver-board, fiber or other self-sustaining composition, which is in itself sound-deadening. Preferably the walls of the casing are separate units, so jointed and held together as to assure the sound-deadening characteristic of 35 the casing. Certain features of the invention relate to clamps by which the desired union of the walls is had; and to certain holding or anchoring means for the clamps, 40 to prevent the same from working loose in the softer material of the casing itself; also to means for holding the hinges to such softer material of the casing, while preserving a smooth interior finish, to prevent fouling of the work-sheets as the latter move over 45 and with the carriage of the machine within the casing.

Other features and advantages will hereinafter appear.

In the accompanying drawings,

Figure 1 is a view of the casing, in cross-sectional, side elevation; the machine being indicated in dotted lines therein.

Figure 2 is a front view, partly cross-sectional, of the casing. 55

Figure 3 is a detail view, in cross-section, through one of the corners of the casing, to show the manner in which the walls are held together.

Figure 4 is a detail view of one of the 60 slot-closing cushions.

The casing is shown as made in two parts, to wit, a body-part 10 and a cover 11, hinged together at 12. The sections 10 and 11 are of some stiff, sound-deadening material, 65 such, for instance, as beaver-board or fiber. The leaves 13 and 14 of the hinge extend lengthwise of the joint 15 of the casing. Strips of metal 16 and 17 are set into grooves or countersinks in the inner faces of the 70 casing-members, and extend lengthwise of the same, to serve as anchoring means for screws 18, which pass through the same, and through the board and the leaves of the hinge, and which are held in place by nuts 19. By countersinking the strips 16 and 75 17 in the faces of the casing-sections and by countersinking the heads of the screws 18 in the strips, a smooth surface is maintained on the inside of the casing, to prevent fouling of the paper on the countersunk members. A base-piece 20, preferably provided with a pad 20^a of felt, is secured by pins or screws 21 to the lower edges of the 80 casing-body 10. Set in an opening in the forward upper portion of the cover is a window-pane 22, of glass or other transparent material, through which the printing being 85 effected upon the platen, within the casing, may be observed. The pane 22 rests on a ledge 23, forming part of the window-frame, and a binding or packing strip 24 embraces the edges thereof. Suitable clamps 25 are provided for holding the pane in its frame. 90

The machine 26, within the casing, is provided with the usual front feet 27 and rear feet 28. The keyboard-extension 29 of the machine projects through a suitable opening 30 in the front wall 31 of the casing-body. The typewriter-carriage 32 is mount- 95 100

ed to have letter-feed and return movements on the main frame of the machine, and has mounted thereon a carriage-return handle 33, a carriage-release lever or handle 34 and a line-space lever or handle 35. In Figure 1, these handles are shown as projecting to the outside of the front wall of the casing, so as to be accessible to the operator. Since these handles must move with the carriage, the 10 front wall of the casing is slotted horizontally and longitudinally thereof. In the drawings, this slot is shown at 36, formed by the lower forward edge 37 of the cover and by the upper edge 38 of the front wall 31 of 15 the casing-body. This slot 36 is, however, practically closed by two resilient, flexible cushions 39 and 40; the cushion 39 being secured by screws 41 passing through lips 37^a on the edge 37 of the cover, and the 20 cushion 40 by screws 42 passing through lips 38^a on the edge 38 of the casing-body, the screws 41 and 42 being received in metal strips 37^b and 38^b behind the rear lips 37^a and 38^a, respectively. The cushions, in effect, 25 close the slot 36, being in contact with each other except where the handles 33, 34 and 35 protrude between the same. The yieldable, flexible character of the cushions permits movement of the handles therealong as the 30 carriage is moved in one or the other direction.

When the casing-cover is open, the typewriting machine may be inserted into the casing through the open top of the casing-body. In the form of the casing shown, the machine is inserted with its keyboard-extension tilted downward and forward. Thus tilted, the keyboard-extension is passed through the hole or opening 30 in the front wall of the casing, and is then brought forward, and the machine lowered until the feet thereof rest upon the base-piece 20, with the rear feet 28 thereof in locators 43. These locators are in the form of 35 ears, preferably of metal, secured by screws 44 to the lower edges of the casing-body; and are provided with holes 45 to receive the rear feet. Lips 46, upturned out of the locators, define the holes 45 and provide ample 40 lateral bearing for the feet. To allow for proper play of the keys 47, the front wall of the casing-body, above the keys, may be cut or tapered inward, as indicated at 48.

Clamps, set along the joints formed by the 45 casing-walls, hold the latter together. These clamps comprise blocks 49, set into the corners, and having wings 50 projecting into grooves 51 in the inner faces of the casing-walls. Anchoring or holding strips 52, for screws 53, are counter-sunk in the outer faces of the walls, opposite the blocks 49; and the screws 53 pass through the strips 52 and through the casing-walls, and are threaded into the blocks 55. In this manner, the walls are not only

held securely together, but the joints are held tightly closed, to maintain the sound-deadening character of the casing.

As shown in Figure 2, the casing has the usual upward and lateral outward flare, to 70 provide space in the upper part thereof, for movement of the carriage in letter-feed and return directions. The cover is supported upon the casing-body at the joint 15, at the rear thereof, by means of the hinges; and, 75 at the front, the cushion 40 supports the cushion 39 of the cover. As shown in Figure 2, the cover side walls overlap the upper edges of the side walls of the casing-body.

The slot-closing cushions 39 and 40 may 80 be readily replaced by new ones when they become worn. To facilitate this replacement, the cushions are held between metal strips or bars 55 riveted together so that they may be readily inserted into slots 56 and 57 85 formed respectively by the lips 37^a and 38^a. The bars 55 are provided with holes to permit the screws 41 and 42 to pass freely through them.

Variations may be resorted to within the 90 scope of the invention, and portions of the improvements may be used without others.

Having thus described my invention, I claim:

1. A casing for a typewriting machine, in 95 two sections, each composed of sheets of self-sustaining sound-deadening composition attached at its edges to form sound-proof joints, one of the sections being a cover hinged to the other section at the rear of 100 the casing, said cover-section having the lower edge of its rear wall beveled, the other section having the upper edge of its rear wall beveled, and means for securing the leaves of the hinge to the board-material of 105 the casing-sections, while maintaining a smooth interior finish, comprising strips of metal countersunk in the inner faces of the casing-sections, and screws passing through said strips and through the casing-walls to 110 the leaves of the hinge.

2. A sound-deadening casing for a typewriting machine comprising a body-section composed of a plurality of sheets of beaver-board or other self-sustaining sound-deadening composition and from which the keyboard of the machine projects, a cover composed of a plurality of sheets of such material openable for the insertion or removal of the machine, and means for clampingly connecting said sheets at their meeting edges, locators for the rear feet of the machine comprising metal ears having holes therein to receive the rear feet, and screws for securing the ears to the lower edges of 120 the casing-body.

3. A sound-deadening casing for a typewriting machine comprising sections composed of a plurality of sheets of beaver-board or other self-sustaining sound-deaden- 130

ing composition and from which the keyboard of the machine projects, a cover composed of a plurality of sheets of such material openable for the insertion or removal 5 of the machine, locators for the rear feet of the machine comprising metal ears having holes therein to receive the rear feet, screws for securing the ears to the lower edges of the casing-body, and a base-piece of 10 sound-deadening material secured to the lower edges of the casing-body below the locators.

4. In a sound-deadening casing for a type-writing machine, in combination, a body-part comprising side walls flared outwardly at the top to accommodate the travel of the typewriter-carriage, a front wall with an opening through which the keyboard projects, a cover openable for insertion and removal 20 of the machine and to give access to the work, locators to receive the rear feet of the machine to position the machine in the casing, a base on which the machine and said body-part rest, and devices extending 25 through said base and said locators to secure them to said body-part.

5. In a sound-deadening casing for a type-writing machine, in combination, a body-part comprising side walls flared outwardly at the top to accommodate the travel of the typewriter-carriage, a front wall with an opening through which the keyboard projects, a cover openable for insertion and removal 30 of the machine and to give access to the work, locators to receive the rear feet of the machine to position the machine in the casing, devices to hold the rearward portions of said locators against the lower edges of said rear wall, a base on which the machine and said body-part rest, and devices extending through said base to secure it to 35 said body-part.

6. In a sound-deadening casing for a type-writing machine, in combination, an open-top body-portion having separate walls of self-sustaining sound-deadening composition, including a rear wall, side walls outwardly flared to accommodate the travel of the carriage, and a front wall through which 40 the keyboard projects, all of said walls being connected to form a sound-proof joint; and a cover pivotally mounted on the body-part and comprising a sheet of self-sustaining sound-deadening composition forming 45 the rear wall of the cover and curved inwardly and downwardly to form the top of the cover, and sheets of self-sustaining sound-deadening composition forming the side walls of said cover, all of said sheets 50 being so connected as to form sound-proof joints.

7. In a sound-deadening casing for a type-writing machine, in combination, a body-portion comprising a sound-deadening base 55 on which the typewriter rests, a rear wall

consisting of a sheet of sound-deadening composition fastened to said base, side walls consisting of sheets of sound-deadening composition flared upwardly and outwardly to accommodate the travel of the typewriter-carriage and secured at their lower edges to said base and at their rear edges to said rear wall, and a front wall consisting of a sheet of sound-deadening composition secured to the front edges of said side walls and having an opening through which the keyboard of the typewriter projects; and a cover consisting of a sheet of sound-deadening composition hinged to the top edge of said rear wall of the body-portion and curved forwardly and downwardly to form at its front edge a slot with the upper edge of the front wall of the body-portion, and side walls consisting of sheets of sound-deadening composition connected to the 70 edges of the hinged sheet.

8. In a sound-deadening casing for a type-writing machine, in combination, a body-portion comprising a sound-deadening base on which the typewriter rests, a rear wall 75 consisting of a sheet of sound-deadening composition fastened to said base, side walls consisting of sheets of sound-deadening composition flared upwardly and outwardly to accommodate the travel of the typewriter-carriage and secured at their lower edges to said base and forming at their rear edges miter-joints with the side edges of said rear wall, and a front wall consisting of a sheet of sound-deadening composition forming 80 miter-joints with the front edges of said side walls and having an opening through which the keyboard of the typewriter projects; and a cover consisting of a sheet of sound-deadening composition hinged to the top edge of said rear wall of the body-portion and curved forwardly and downwardly to form 85 at its front edge a slot with the upper edge of the front wall of the body-portion, and side walls consisting of sheets of sound-deadening composition connected to the edges of the hinged sheet.

9. In a sound-deadening casing for a typewriter machine, in combination, a body-portion comprising a sound-deadening base on which the typewriter rests, a rear wall 90 consisting of a sheet of sound-deadening composition fastened to said base, side walls consisting of sheets of sound-deadening composition flared upwardly and outwardly to accommodate the travel of the typewriter-carriage and secured at their lower edges to said base and forming at their rear edges miter-joints with the side edges of said rear wall, a front wall consisting of a sheet of sound-deadening composition forming 95 miter-joints with the front edges of said side walls and having an opening through which the keyboard of the typewriter projects; and a cover consisting of a sheet of sound-deadening composition hinged to the top edge of said rear wall of the body-portion and curved forwardly and downwardly to form 100 at its front edge a slot with the upper edge of the front wall of the body-portion, and side walls consisting of sheets of sound-deadening composition forming miter-joints with the edges of the hinged sheet.

10. In a sound-deadening casing for a typewriter machine, in combination, a body-portion comprising a sound-deadening base on which the typewriter rests, a rear wall 105 consisting of a sheet of sound-deadening composition fastened to said base, side walls consisting of sheets of sound-deadening composition flared upwardly and outwardly to accommodate the travel of the typewriter-carriage and secured at their lower edges to said base and forming at their rear edges miter-joints with the side edges of said rear wall, a front wall consisting of a sheet of sound-deadening composition forming 110 miter-joints with the front edges of said side walls and having an opening through which the keyboard of the typewriter projects; and a cover consisting of a sheet of sound-deadening composition hinged to the top edge of said rear wall of the body-portion and curved forwardly and downwardly to form 115 at its front edge a slot with the upper edge of the front wall of the body-portion, and side walls consisting of sheets of sound-deadening composition forming miter-joints with the edges of the hinged sheet.

11. In a sound-deadening casing for a typewriter machine, in combination, a body-portion comprising a sound-deadening base on which the typewriter rests, a rear wall 120 consisting of a sheet of sound-deadening composition fastened to said base, side walls consisting of sheets of sound-deadening composition flared upwardly and outwardly to accommodate the travel of the typewriter-carriage and secured at their lower edges to said base and forming at their rear edges miter-joints with the side edges of said rear wall, a front wall consisting of a sheet of sound-deadening composition forming 125 miter-joints with the front edges of said side walls and having an opening through which the keyboard of the typewriter projects; and a cover consisting of a sheet of sound-deadening composition hinged to the top edge of said rear wall of the body-portion and curved forwardly and downwardly to form 130 at its front edge a slot with the upper edge of the front wall of the body-portion, and side walls consisting of sheets of sound-deadening composition forming miter-joints with the front edges of said side walls and having an opening through which the keyboard of the typewriter projects; and clamps to secure said

walls at said miter-joints; and a cover consisting of a sheet of sound-deadening composition hinged to the top edge of said rear wall of the body-portion and curved forwardly and downwardly to form at its front edge a slot with the upper edge of the front wall of the body-portion, side walls consisting of sheets of sound-deadening composi-

tion forming miter-joints with the edges of the hinged sheet, and holding clamps for 10 said miter-joints.

10. The casing substantially as described and illustrated in the accompanying drawings.

JOHN WALDHEIM.
